POLISHING AND GRINDING TABLE

Clyde H. McElroy, 1609 W. 19th Ave., Kennewick, Wash.

Filed Dec. 20, 1956, Ser. No. 629,719

6 Claims. (Cl. 125—30)

This invention comprises a novel and useful polishing and grinding table and more particularly relates to an apparatus for effectively polishing and grinding surfaces upon objects and especially for use by lapidaries for polishing stones and the like.

The principal object of this invention is to provide an apparatus for polishing and grinding surfaces such as those of precious and semiprecious stones, and whereby the grinding and polishing surface shall be subjected to a vibratory motion.

A further object of the invention is to provide an apparatus in conformity with the preceding object which will readily permit the presenting of various different grinding and polishing surfaces for operating upon the article to be abraded or polished.

A still further object of the invention is to provide an apparatus in conformity with the preceding objects wherein a series of different polishing and grinding surfaces may be interchangeably associated with the apparatus.

And a still further important object of the invention is to provide an apparatus in conformity with the above mentioned objects wherein the various selected grinding and polishing surfaces shall be mounted in an improved manner and subjected to a rapid vibratory motion by a simple and effective mechanism.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of one suitable form of apparatus in accordance with the principles of this invention, the apparatus illustrated including a removable attachment for providing an additional interchangeable series of grinding and polishing surfaces;

Figure 2 is an enlarged vertical transverse sectional view taken through the apparatus of Figure 1, parts being broken away;

Figure 3 is a bottom plan view of the apparatus of Figures 1 and 2;

Figure 4 is a bottom plan view showing the lower polishing and grinding surface of the attachment illustrated in Figure 2;

Figure 5 is a detail view taken on an enlarged scale upon the vertical transverse section indicated by the section line 5—5 of Figure 4;

Figure 6 is a detail view in horizontal section taken on an enlarged scale substantially upon the plane indicated by section line 6—6 of Figure 2 and showing the actuating means for imparting a rapid vibratory motion to the carriage of the apparatus; and,

Figure 7 is a detail view taken in vertical section on an enlarged scale substantially upon the plane indicated by section line 7—7 of Figure 3 and showing one of

2

the leveling, supporting and centering means of the vibratory carriage of the apparatus.

The fundamental aim of this invention is to provide a simple and compact form of apparatus whereby a rapid vibratory movement in a horizontal plane may be given to a carriage, which, in turn, carries a series of selected polishing and abrading surfaces for grinding and polishing an article held thereagainst, and whereby various sets of different polishing and grinding surfaces may be interchangeably employed with the apparatus.

In accordance with this purpose, the apparatus illustrated consists of a supporting stand indicated generally by the numeral 10 and which preferably comprises a plurality of legs 12 which, as shown, may conveniently be generally L-shaped in cross section. Indicated generally by the numeral 14 is a supporting frame consisting of vertical frame members 16 secured to the inside surfaces of each of the legs 12 in spaced relation to the top of the same to thus provide a rectangular open frame. At the bottom of the members 16 are diagonally disposed flat strips 17 which, as shown best in Figure 3, intersect at the central portion of the frame.

Indicated generally by the numeral 18 is a reciprocatory carriage which is supported centrally of the hollow rectangular frame 14 as set forth hereinafter and is subjected to a vibratory motion in a horizontal plane by a means to be subsequently described. This carriage includes vertically extending side walls 20 which thus provide a rectangular tray having a bottom wall 22 with laterally projecting, apertured lugs 24 at its upper surface which provide means by which the carriage or tray is supported centrally of the hollow frame 14 for vibratory motion in a horizontal plane as set forth herein-after by a means to be subsequently described.

The top surfaces 25 of the side walls 20, as seen in Fig. 5, are provided with dowel pin openings 26 for the reception of dowel pins 28, whereby an attachment indicated generally by the numeral 30 may be detachably and reversibly associated with and carried by the side walls of the carriage 18.

The attachment 30 is a frame or tray-like member of substantially the same size as that of the carriage 18 and consists of vertical side walls 32 which intermediate their top and bottom edges upon their inner surface are provided with a peripheral groove 34 in which is seated a partition 36.

As will be apparent from Figure 5, both the bottom surface 38 and bottom surface 40 of the side walls of the attachment are provided with dowel pin openings 42 for the reception of the dowel pins 28 of the carriage 18, whereby the attachment may be reversibly mounted upon the top surface of the walls 20 of the carriage 18.

At this point it should be observed that the top surface of the bottom wall 22 of the carriage 18 and both the top and bottom surfaces of the partition 36 of the attachment 30 are provided with a plurality of polishing, grinding or abrading surfaces of any desired character thereon. As shown in Figures 4 and 5, criss-cross grooves 43 in the member 36 define therebetween surfaces 45 comprising the polishing or abrading surfaces previously mentioned. The same arrangement is employed with the bottom wall 22. These series of surfaces having different characteristics as to polishing or abrading, upon horizontal vibratory motion of the carriage 18 or of

the attachment 30 when carried thereby, provide a plurality of violently agitated surfaces upon which a stone or other object may be held and thus effectively ground, abraded or polished as desired.

It is obviously necessary merely to reverse the attachment 30 upon the carriage in order to provide an entirely different surface available for the polishing or grinding operations.

Referring now especially to Figure 7, it will be observed that the top portion of each of the legs 12 is provided with a horizontally extending in-turned flange 50 and with a lower parallel underlying apertured lug 52. Slidable in the flange and in the lug is an L-bolt 54 having suitable lock nuts 56 upon its upwardly projecting end, and having at its lower end an eye 58 to which a cable 60 is attached, the latter being also secured to the apertured lugs 24 previously mentioned. A compression spring 62 encircles the rod below the flange 50, being retained as by a collar 64. It will thus be apparent that by adjusting the nuts 56 upon the upper threaded end of the bolt or rod 54 that the carriage 18 may be leveled and will be held centrally of the open frame of the supporting stand of the apparatus.

Depending from the mid-portion of the bottom 22 of the carriage 18 is a ring or annulus 66 secured thereto as by welding 68. This ring provides a central cylindrical recess or cavity 70 constituting a bearing and which receives an eccentric member 72 fixedly secured to a vertically disposed shaft 74. The above mentioned shaft is journaled through a tubular boss 76 welded or otherwise secured to the members 17 at their intersection. By means of pulleys 78 secured to the end of the shaft, and actuated by a belt, not shown, from any suitable source, motion is imparted to the shaft 74, which in turn through the eccentric member 72 causes vibratory motion of the carriage 18 in a horizontal plane, such motion being permitted by the flexing of the supporting cable.

The foregoing is considered as illustrative only of the principles of the invention. Further, since numerous modifications and changes will readily occur to those skilled in the art, it is not desired to limit the invention to the exact construction and operation as shown and described, and accordingly all suitable modifications and equivalents may be resorted to, falling within the scope of the invention as claimed.

What is claimed as new is as follows:

1. A polishing and grinding table comprising a supporting stand including a frame having an opening therein, a carriage loosely received and movable wholly within the confines of said opening, polishing and abrading means carried fixedly by said carriage and movable therewith, means mounted upon said stand and disposed within said frame and outside of said opening and resiliently supporting and centering said carriage in said opening for vibratory movement in the horizontal plane of the frame, vibratory means for causing vibratory motion of said carriage upon said supporting means, said carriage including a platform having upstanding side walls, said supporting and centering means being connected to said side walls and to the sides of said frame, an attachment having means for detachably and reversibly securing the side walls thereof to said carriage side walls whereby the attachment will be vibrated with the carriage, said polishing and abrading means being carried by said attachment, said attachment having reversible abrading surfaces disposed between the attachment side walls with said last mentioned means being disposed on both of said surfaces.

2. A polishing and grinding table comprising a supporting stand including a frame having an opening therein, a carriage including a bottom wall and upstanding side walls thereon, resilient support means secured to said carriage and frame and suspending the carriage in

said opening for vibratory movement in all directions in a horizontal plane, driving means connected to said carriage and causing vibratory motion thereof, said carriage having an abrading means on said bottom wall, an attachment comprising side walls and an abrading means extending between and carried by said walls, means detachably securing the attachment upon said carriage, said abrading means including a member having abrading surfaces on both sides thereof, said securing means retaining said attachment upon said carriage in reversible positions.

3. A polishing and grinding table comprising a supporting stand including a frame having an opening therein, a carriage including a bottom wall and upstanding side walls thereon, resilient support means secured to said carriage and frame and suspending the carriage in said opening for vibratory movement in all directions in a horizontal plane, driving means connected to said carriage and causing vibratory motion thereof, said carriage having an abrading means on said bottom wall, an attachment comprising side walls and an abrading means extending between and carried by said walls, means detachably securing the attachment upon said carriage, said abrading means including a member having abrading surfaces on both sides thereof, said securing means retaining said attachment upon said carriage in reversible positions, said carriage and attachment having their side walls disposed for endwise abutting engagement.

4. The combination of claim 3 wherein said securing means comprises registering bores on the top surface of the end walls of said carriage and the top and bottom surfaces of the attachment end walls and fasteners engaged in the bores of the carriage and selectively in the bores of the top and bottom surfaces of said attachment side walls.

5. A lapidary's polishing and grinding table comprising a supporting stand including a frame with straight vertical legs spaced to define an opening therebetween, a carriage loosely mounted wholly within said opening and movable with both a gyratory, oscillatory and vertical movement, polishing and abrading means carried fixedly by said carriage within the confines thereof and movable therewith, flexible means supporting said carriage from said legs for gyratory movement in a horizontal plane and for limited vertical movement, said supporting means being connected to the exterior of said carriage at its upper end and to said legs outside of said opening whereby said supporting means and its connections will not limit movement of said carriage in said opening, vibratory means for causing a uniform and continuous smooth vibratory motion of said carriage, said carriage having a bottom wall with marginal side walls thereon, an attachment for said carriage and having polishing and abrading surfaces thereon, means detachably securing said attachment to the walls of said carriage for mounting thereon and extending upwards therefrom.

6. The combination of claim 5 wherein said attachment includes reversible surfaces each having said polishing and abrading surfaces thereon.
